UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

ALL-METAL-DOOR CONSTRUCTION.

Application filed March 16, 1925. Serial No. 15,938.

This invention relates generally to doors for vehicle bodies and consists of certain novel features of construction, combinations and arrangements of parts as will be more 5 fully described and particularly pointed out in the appended claims.

In the accompanying drawings:

Figure 1 is an elevation of the inner side 10 of the door.

Figure 2 is an elevation of the outer side 15 of the door.

Figure 3 is a sectional view taken on the line 3—3 of Figure 1.

Figure 4 is a fragmentary sectional view 15 taken on the line 4—4 of Figure 1.

Figure 5 is a fragmentary sectional view 20 taken on the line 5—5 of Figure 1.

Figure 6 is a fragmentary sectional view 25 taken on the line 6—6 of Figure 1.

Figure 7 is a fragmentary sectional view 30 taken on the line 7—7 of Figure 1.

Figure 8 is a detail perspective view of 35 the removable header.

Referring now to the drawings, the 40 numeral 1 designates a door that is preferably 45 constructed entirely of metal and is designed for vehicle bodies of the closed type. As shown, this door is preferably provided with two metal panels 2 and 3 respectively that 50 are secured to suitable metal pillars or upright members 4 and cooperate therewith to 55 form a rigid box-like construction. The outer panel 2 preferably extends the full length of the upright members and is preferably 60 provided at its upper end with a suitable window opening 5, while the inner panel 3 preferably 65 extends from the lower end of the upright members 4 to a point in line with the lower edge of the window 70 opening 5 and is preferably provided adjacent to its lower end with a suitable opening 6 to permit access to the space between 75 the panels 2 and 3 respectively.

In order that the occupants of the vehicle 80 will have the maximum vision, the upright members 4 are preferably relatively narrow and are provided at their inner edges with longitudinally extending channel-shaped 85 portions 7 that project laterally therefrom and constitute runways for a vertically movable glass panel 8. Any suitable means (not 90 shown) may be used to operate the glass panel 8.

To provide a rigid construction, the inner 95 panel 3 is preferably provided at its top,

bottom and side edges with suitable flanges 9, 10, and 11 respectively that preferably project inwardly and serve to stiffen the panel 3. As shown, the side flanges 11 are provided at their inner edges with lateral 60 extensions 12 that are preferably welded to the inner flanges 13 of the channel runways 7; the lower flange 10 is provided at its inner edge with a depending extension 14; while the upper flange 9 terminates short 65 of the glass panel 8 and is preferably covered by a suitable metal finish strip 15. In the process of construction, the lateral extensions 12 of the side flanges 11 are preferably welded to the inner flanges 13 of the 70 channel runways, whereupon a channel-shaped cross member 16 is preferably welded at its opposite ends to the uprights 4 at the upper ends thereof. The outer panel 2 is then secured to the uprights 4, inner panel 75 3 and cross member 16. This is accomplished by bending suitable marginal flanges 17 of the outer panel around suitable lateral flanges 18 at the outer edges of the upright members 4, and subsequently welding the return bent flanges 17 to the flanges 18. The lower marginal flange 19 of the outer panel 2 is bent upwardly around the depending extension 14 of the inner panel 3, while the upper marginal flange 20 of the outer panel 85 is preferably welded to the upper flange 21 of the channel cross member 16.

In order that the door will have a neat appearance around the window opening 5, the outer panel 2 is preferably provided at 90 the top, bottom and side edges of the opening 5 with inwardly extending flanges 22, 23 and 24 respectively. As shown, the upper flange 22 constitutes the window header finish strip and is preferably welded to the 95 lower flange 25 of the channel cross member 16; the side flanges 24 are preferably welded to the inner face of the upright members 4 and are preferably provided with the lateral flanges 26 that are welded to the outer 100 flanges 27 of the runways 7; while the lower flange 23 constitutes the window sill and is preferably return bent adjacent to the flange 9 of the inner panel 3. In order that a weather seal may be formed between the 105 glass panel 8 and the flanges 9 and 23 respectively of the outer and inner panels, a resilient weather strip 28 is preferably secured to the inner face and flange 9 of the inner panel 3 and is engageable with the 110

inner face of the glass panel 8, while a similar weather strip 29 is preferably secured to a depending extension 30 of the flange 23 and is engageable with the outer face of the 5 glass panel 8.

As shown in Figure 3 of the drawings, the flanges 21 and 25 respectively of the channel cross member 16 preferably terminate at a point in-substantial alignment with 10 the outer flanges 27 of the channel runways 7, thus, the glass panel 8 may be readily inserted into or removed from the runways 7 by merely sliding the panel past the channel cross member 16. Normally the upper ends 15 of the runways 7 are closed by a metal header 31 that preferably carries a channel-shaped resilient strip 32 for receiving the upper edge of the glass panel 8. As shown, this header 32 is preferably channel-shaped 20 in cross section and is provided at the outer and inner edges of the lower flange 33 with a longitudinally extending bead 34 and a depending extension 35 that cooperate to hold the resilient strip 32. To attach the header 25 31 to the door, the depending extension 35 is hooked over an upstanding flange 36 at the inner edge of the flange 22, while the upper flange 37 of the header 31 is slipped between the upper flange 20 of the outer 30 panel and suitable lugs 38 projecting inwardly from the upper flange 21 of the cross member 16 and is held in position by means of suitable screws 39.

Thus, from the foregoing description, it 35 will be readily apparent that the glass panel 8 may be readily inserted in or removed from the runways 7 by adjusting the removable header 31. Inasmuch as the runways 7 are an integral part of the upright members 4, it will also be apparent that the runways 40 7 will be uniform so that the glass panel 8 will travel in a straight line. Moreover, the separate strips of garnish molding ordinarily employed for receiving the glass panel 45 at the sides of the window opening in the door have been dispensed with entirely. Furthermore the upright members 4 have small cross sections, hence the vision of the occupants of the vehicle is materially increased and a wider glass panel 8 may be 50 employed. Moreover the panels 2 and 3 respectively and the uprights 4 are connected together, in such a way that the door will be effectively prevented from weaving and 55 twisting or otherwise weakening while in use. It will also be noted that the outer panel 2 is secured directly to the inner panel 3 at the lower end of the door, thus a strong joint is provided and the cross bar usually 60 provided at this point has been dispensed with entirely. Inasmuch as a light gauge metal is used for the outer panel 2, the metal may be rounded at the corners as shown at 65 40 to provide a neat and attractive appearance.

While it is believed that from the foregoing description the nature and advantages of the invention may be readily apparent, I desire to have it understood that I do not limit myself to what is herein shown and 70 described and that such changes may be resorted to when desired as fall within the scope of what is claimed.

What I claim as my invention is:

1. In a door, a pair of spaced upright 75 members having longitudinally extending runways for a glass panel, a metallic panel secured to said upright members having an inwardly extending flange at its upper edge terminating in an upstanding flange, and a 80 removable header closing the upper ends of said runways and having a depending flange hooked over the upstanding flange and resting on said inwardly extending flange.

2. In a door, a pair of spaced upright 85 members having lateral flanges, and longitudinally extending runways for a movable glass panel, a metal panel secured to the lateral flanges of said upright members and having an inwardly extending flange at its 90 upper edge terminating in an upstanding flange, a header closing the upper ends of 95 said runways and having a depending flange engaging the upstanding flange and resting on said inwardly extending flange, and means detachably securing the header to the metal panel.

3. In a door, a pair of upright members having longitudinally extending runways, a glass panel movable in said runways, a metal 100 panel secured to said upright members, and a header comprising a channel-shaped member secured to said panel above said runways, one wall of said member having a longitudinally extending bead and a depending extension for holding a channel shaped 105 strip in position to receive an edge of the glass panel.

4. In a door, a pair of upright members having longitudinally extending runways 110 for a glass panel, a cross member terminally secured to said upright members, a removable header secured to said cross member and normally closing the upper ends of the runways, and a panel secured to said upright 115 members and having a window opening therin at its upper end, said panel also having a lateral flange at one edge of the opening supporting the header.

5. A door having an outer panel provided 120 with a window opening, laterally spaced upright members secured to said panel, channel runways for a window carried by said upright members, said panel having an inwardly extending flange at the upper edge 125 of said window opening, said flange terminating at the outer side walls of said runways and having an upstanding flange at its inner edge, a channel-shaped cross member terminally secured to said upright mem- 130

- bers at the upper ends thereof, said cross member lying on one side and opening inwardly from said panel, the inner free edges of said cross member terminating short of 5 said upstanding flange, and a removable channel-shaped header secured to said cross member, said header lying on one side and opening toward said outer panel, one wall of said header being secured to the upper 10 wall of the cross member, and another wall of said header having a portion supported upon the inwardly extending flange of said outer panel.
6. A door having an outer panel provided 15 with a window opening, laterally spaced upright members secured to said panel, channel runways carried by said upright members, a window movable in said runways, a cross member terminally secured to said upright members at the upper ends thereof, said outer panel having an inwardly extending flange at the upper edge of the window opening, said flange terminating short of the outer side walls of said runways to permit 25 insertion and removal of a window panel past said cross bar, said inwardly extending flange having an upstanding flange at its inner edge, a window header secured to said cross member and having a portion held by 30 the upstanding flange aforesaid upon said inwardly extending flange, and a yieldable strip carried by said header for receiving an edge of said window.
7. A door having a pair of upright members 35 provided with longitudinally extending runways, a glass panel movable in said runways, a cross bar terminally secured to said upright members at one side of said runways, and a header comprising a channel-shaped member transversely secured to said cross bar above said runways, said channel-shaped member lying on one side, the lower side wall of said channel-shaped member having a longitudinally extending bead and 40 a depending flange, and a channel strip held by said bead and flange in position to receive an edge of said glass panel.
8. In a door, a pair of upright members having longitudinally extending runways, a 45 glass panel movable in said runways, a metal panel secured to said upright members, and a header detachably secured to said panel above said runways, a cross bar terminally secured to said upright members and having a longitudinally extending bead and a depending flange, and an inverted channel strip held by said bead and flange in a position to receive an edge of the glass panel.
9. A door having an outer panel provided 50 with a window opening, and laterally spaced upright members secured to said panel formed with channel shaped runways, said outer panel having inwardly extending flanges at the side edges of said window 55 opening secured to the inner face of said upright members, and lateral flanges projecting from the flanges aforesaid extending into said channel-shaped runway and secured to the outer walls thereof.
10. In a door, the combination with spaced 70 inner and outer panels, of an upright member having a relatively small cross sectional area and formed from a single sheet of metal, said upright member having a lateral flange at one edge secured to the outer panel, 75 and having a longitudinally extending runway for a vertically movable glass panel formed at the inner edge and secured to the inner panel.
11. In a door having a window opening 80 therein, a metal pillar formed with a channel shaped portion constituting a runway for a vertically movable glass panel, said pillar having a flange extending outwardly from the opening and having an intermediate portion at the side edge of said opening connecting said flange and channel shaped portion, and a panel formed with a window opening therein having portions secured to said flange, intermediate portion 85 and outer wall of said channel shaped portion.
12. In a door having a window opening 90 therein, a pillar formed with a channel-shaped portion constituting a runway for a vertically movable glass panel, the outer wall of said channel-shaped portion having a flange projecting outwardly from the inner edge thereof and terminating in a lateral flange, and a panel formed with a window 95 opening therein having spaced inner and outer lateral flanges secured respectively to the outer wall of said channel-shaped runway and the lateral flange formed on said pillar, said panel further having a portion connecting the inner and outer flanges thereof and secured to the outwardly projecting flange of said pillar.
13. An automobile door having a slidable window arranged therein comprising a jamb 110 rail formed by an integral metal stamping, said rail having oppositely presenting channels providing a rabbet, a guide for the window, and a strengthening element for the door.
14. An automobile door having a slidable window arranged therein comprising a jamb 115 rail formed by an integral metal stamping, said rail having oppositely extending flanges along its edges and oppositely presenting channels intermediate its edges.
15. An automobile door having a slidable window arranged therein comprising a jamb rail provided with oppositely presenting channels having a common arm, whereby a 120 guide for the window and a strengthening element for the rail are provided.
16. An automobile door having a slidable window arranged therein comprising a jamb 125 rail having its edges flanged in opposite di- 130

rections and oppositely presenting channels intermediate the edges, one of said edges forming the overlap for the door and one of the said channels forming a guide for the window.

17. A door rail for vehicle doors having a sliding window comprising a unitary sheet metal stamping extending the length of the door and formed with a window guiding channel.

18. An automobile door having a slidable window arranged therein comprising a door rail at the side of the window opening, of web cross section having a transversely extending jamb face portion and an outer door overlap portion, the transverse portion being formed with a hollow rib, the inner wall of which forms the side of the glass run.

In testimony whereof I affix my signature.

WILLIAM MARSHALL.
